UNITED STATES PATENT OFFICE

FRANK N. GEORGE, OF BUFFALO, NEW YORK

APPARATUS FOR STRAINING PAINT

Application filed July 23, 1929. Serial No. 380,329.

My invention relates to improvements in an apparatus for straining paint and like material, and filling cans or other containers.

One of the objects of my invention is to provide an apparatus whereby paint can be continuously fed to the filler tanks from which cans or other containers are to be filled with paint, and wherein provision is made for straining the paint so that it will be delivered to the filling spigots or other outlets and be ready for the market upon closing of the containers.

Another object of my invention is the provision of means for intermittently furnishing compressed air, contrariwise to the flow of the paint at a suitable point, or points, between the mixing vat or vats and the filling point or points at which the cans or other containers are to be filled.

A further object of my invention is the provision of an apparatus in which a plurality of filler tanks are provided and also a plurality of mixing vats, all associated with pressure-controlling means operating to intermittently admit compressed air to the filler tanks and allow the escape of the air therefrom, and in placing within or upon the filler tanks, screening devices through which the paint delivered from the mixing vats is delivered to the filler tanks contrary to the direction of the air escaping or attempting to escape from said filler tanks.

Other objects of my invention are to provide new and novel equipment for filling cans or other containers with paint ready for the market, whereby the paint will be properly strained without retarding the flow of the same and thus reducing the capacity of the apparatus.

With the above and other objects in view, my invention consists in the novel features of construction and in the arrangement and combination of parts to be hereinafter described and more particularly pointed out in the subjoined claims.

In the drawings:—

Fig. 1 is a view showing parts of my novel apparatus or equipment in section and part 50 in elevation.

Fig. 2 is a horizontal section, taken on line 2—2, Fig. 1.

Fig. 3 is a transverse section, taken on line 3—3, Fig. 1.

Fig. 4 is a longitudinal section through my improved pressure-control valve, taken on line 4—4, Fig. 2.

Fig. 5 is a longitudinal section through part of said valve, taken on line 5—5, Fig. 4.

Fig. 6 is a transverse section, taken on line 6—6, Fig. 4.

This new and novel apparatus or equipment is adapted to be supported upon one or more floors of a building, and in the drawings I have shown two floors of a building, in which 7 designates one floor and 8 a second floor, and on which latter suitable mixing vats 9, 10, 11, of any type, are supported. While I have shown three mixing vats, one or any other number of such vats may be used.

These vats may contain paint of the same or different colors or kind, and they have delivery pipes 12, 13, 14, respectively, connected to the bottoms thereof and extending through the floor 8; said delivery pipes terminating above filler tanks 15, 16, 17, respectively. These tanks need not be equal in number to the mixing vats and may be of any desired size or construction. They may rest upon a table or other elevated support 18 standing upon the floor 7, or be otherwise supported. The several pipes 12, 13 and 14 are connected together by horizontal connector pipes 19, each of which has a shut-off valve 20 therein; and a shut-off valve 21 is arranged in each of the delivery pipes above its connection with the horizontal pipe or pipes 19. The delivery pipes also have shut-off valves 22 therein between the horizontal pipe or pipes 19 and their lower or outlet ends.

The filler tanks 15, 16 and 17 are open at their upper ends, and screen pans 23 having downwardly-tapered peripheral walls or body portions extend into the open ends of said tanks and have frictional contact with the peripheral walls thereof.

The peripheral walls of the filler tanks are somewhat yielding and conformable to the exact shape of the screen pans so that when 100

the screen pans are placed thereinto, said pans are rendered substantially air-tight around the circular region where they receive support from the tank walls. Said screen pans are open at the bottom and their downwardly-tapered peripheral walls are provided with inwardly-directed flanges 24 which support screens 25 placed within the pans and serving as foraminous bottoms therefor. Under this arrangement, paint from any mixing vat or vats may be delivered to all of the filler tanks, or paint from each vat may be delivered to any individual or any number of filler tanks less than the complete number used in the apparatus or plant.

Normally, the valves 20 in the horizontal connector pipes 19 are closed, and upon opening the valves 21 and 22 of each delivery pipe, paint will be delivered from each mixing vat into one of the filler tanks.

If, for example, it is desired to deliver paint from the mixing vat 9 to the filler tanks 15 and 16, the valves 21 and 22 in the delivery pipe 12, the valve 22 in the delivery pipe 13 and the valve 20 in the horizontal connector pipe between said two delivery pipes are opened, whereupon the paint will flow from the vat 9 to the screen pans 23 of the two filler tanks 15 and 16. If, however, it is desired to deliver paint from each of the mixing vats to a separate filler tank, the valves 20 in the connector pipes 19 are closed and the valves 21 and 22 in each of the delivery pipes opened.

Without further explanation of this pipe and valve arrangement, it will be apparent that paint may be taken selectively from any of the mixing vats and delivered selectively to any desired filler tank or tanks.

The paint delivered into the screen pans passes through the screen or foraminous bottoms of said pans and enters the filler tanks, from which the strained paint is discharged through spigots 26 or other suitable delivery-controlling devices into cans, pails, or other containers 27, which may be of any desired construction. Where paint is to be sold in gallon quantities, pails are usually employed which are closed in any approved manner, and where the paint is to be sold in smaller quantities, cans are usually employed.

It is generally known that paint delivered from mixing vats is not in marketable condition and must therefore be strained before delivering it to the containers in which it is to be sold, and invariably, when straining paint delivered from the mixing vats, the capacity of the plant or apparatus is materially reduced, due to the fact the matter strained out of the paint so clogs the passage or passages in the straining medium that the flow of paint will be stopped, and this necessitates the cleaning of the straining medium

to free the passage or passages of the obstructing matter.

To assure a continuous flow of paint and the continuous filling of the cans, pails, or other containers to be marketed, I have provided new and novel means for maintaining the passages in the screening elements in free and clear condition at all times.

With this end in view I employ a controlled air-supply including an air-controlling valve, and preferably impart variable speed to the valve element of said controlling valve in moving said element from and into open and closed position with reference to its admission of compressed air thereto. In the drawings I have therefore shown as one embodiment of this feature of my invention, a compressed air tank 28 which receives its compressed air from any suitable source through a pipe 29 connected thereto. I also employ a suitable motor; for example, an electric motor 30, which may be supported in any suitable manner, but is shown as hanging from the floor 8, which divides one story of the building from another. A hanger 31 is suspended from the floor 8 and it has a journal for a shaft 32 rotated by means of reduction gearing within a reduction gear box 33 so that the speed of the shaft 32 is considerably reduced from that of the shaft of the motor 30. The means employed for reducing the speed of the shaft 32, which is driven by the motor, may be of any suitable type, and on this shaft I mount a disk 34 which is adapted for continuous rotary movement upon operation of the motor 30, but at greatly reduced speed from that of the motor.

The air controlling valve comprises an elongated cylindrical valve casing 35 to which is connected a compressed air pipe 36 leading from the compressed air tank 28 and having a control valve 37 therein. The valve casing 35 is open at one end, as at 38, and closed at its other end by means of a reducer 39 having an air outlet 40 to which an air pipe 41 is connected, said pipe 41 having branch air pipes 42, 43, 44 connected thereto which lead to the filler tanks 15, 16, 17, respectively, each of said branch pipes having a control valve 45 therein.

Admission of compressed air to the valve casing 35 is controlled by a reciprocating piston-valve 46 within said valve casing, and this valve is operated to control the admission of compressed air through an inlet 47 in the valve casing, into which inlet the air supply pipe 36 is connected. The valve casing 35 has exhaust ports 48, 49 at opposite sides of the inlet 47 along the length of the valve casing for the discharge of the spent or at least utilized air; and the piston-valve 46 is bored out, or made hollow along a portion of its length, as at 50, and near the inner end of this bore or hollowed-out portion it is provided with a port 51, serving as both an inlet

and outlet port. This valve may be provided with packing rings 52, similar to piston rings on an engine piston, to make the valve airtight and prevent the escape of compressed air along the same.

5 A link or connecting rod 53 has one end pivotally connected to the outer end of the piston-valve 46, as at 54, and its other end is pivotally connected eccentrically to the rotating disk 34, as at 55.

10 When the port 51 in the piston-valve 46 is in registration with the inlet 47 in the valve casing, compressed air is allowed to enter the hollow piston-valve, provided the control 15 valve 37 in the air supply pipe 36 is open. This air is delivered through the air pipe 41 to any one or more of the branch pipes connected to the filler tanks, depending on whether or not the valves 45 in said pipes 20 are open or closed. Therefore, air may be selectively supplied to these filler tanks by simple manipulation of the valves 45. It is, of course, understood that when paint is not being supplied to the filler tanks or any 25 of them, the supply of air will be shut off from the tanks.

As the movement of the piston-valve is continuous, although variable during the operation of the motor, the port 51, which has 30 served as an air inlet when passing over the inlet port 47 in the valve casing, is moved either to the outlet port 48 or 49, depending on the direction of movement of said valve, and at such times the port 51 in the piston- 35 valve becomes an air exhaust port and allows the air within the pipe 41; the valve casing 35, and the piston-valve 46 to escape, or at least causes a reduction of the air pressure to atmospheric pressure within such parts.

40 Due to the fact that the connecting rod 53 is eccentrically connected to the rotating disk 34, which may be any other eccentric device, such as a crank or the like, the conversion of the rotary movement of said disk to reciprocating movement of the piston-valve will result in variable movement of said valve, due to the fact that said valve will be caused to travel along a greater range of movement while the pivot 55 of its connecting rod 45 travels through the upper or lower quarter of its circular path of movement than when traveling through the intermediate or side quarters of its circular path, as viewed in Fig. 4; and this quick range of movement, 50 as illustrated in the drawings, preferably occurs during the time the port 51 in the piston-valve travels between the two exhaust ports 48 and 49 of the piston casing. Therefore, the charge of compressed air admitted to the piston-valve occurs over a comparatively short period of time in the cycle of movement of the piston-valve; whereas, when the port 51 in said piston-valve approaches or at 55 least reaches either of the exhaust ports 48 or 49, the speed of movement of the piston-

valve is reduced so that the port 51 in said valve will be in registration with the exhaust port 48, or the exhaust port 49 over a comparatively long period of time, especially since said exhaust ports are considerably 70 longer than the port 51. Said last-mentioned port 51 is maintained in line with or in operative to the exhaust port 48 during a considerable portion of its movement when at the left hand end of its range of travel, as viewed 75 in Fig. 4, and in line with the port 49 during a like period of time when the piston-valve is at the right hand end of its movement, as viewed in said figure. When the port 51 in the piston-valve is open to either of the exhaust ports 48, 49, compressed air delivered to the pipe 41, the valve casing, and the said valve has what may be termed a free escape 80 to atmospheric air.

It is, of course, to be understood that matter 85 which cannot pass through the meshes of the screens, or openings of the foraminous bottoms of the screen pans, lodges upon said bottoms and tends to prevent, or at least retard, the passage of free flowing paint through the 90 said bottoms. Under present day methods, regardless of the type of screen devices used, shutting off the flow of paint from the mixing vats is found necessary in order to remove the clogging matter from the devices, either 95 by replacing the devices with others that have been cleaned, or by removing the sediment adhering to the devices and filling the openings in the same.

With my invention, compressed air is delivered 100 into the filler tanks between the level of the filtered paint therein and the paint screens, and this air tends to quicken the flow of paint from the filler tanks when in the act of filling cans or other similar vessels and at the same time lifts the foreign or clogging matter consisting of pigments, scum and the like, from the screen so as to allow the passage 105 of paint through said screen. This air is admitted to the filler tanks for comparatively short periods only, as will be clear from the description of the controlling valve.

When said valve is in the position shown in Fig. 4 and moving to the right, compressed air is admitted to the valve and immediately 110 enters the filler tanks; assuming the valves 45 in the branch pipes leading to said tanks to be open. Admission of air is allowed so long as any portion of the port 51 in the piston-valve or any portion thereof, remains 115 uncovered by the inlet port 47; but the instant said port 51 completely passes the inlet port 47 in the valve casing, the air is shut off and no opportunity for the escape of air from the filler tanks and their connections is 120 offered, except upwardly through the foraminous bottoms of the screen pans 23, until the port 51 in the piston-valve is opened by passing the exhaust port 49 in the valve cas- 125 ing. The pressure of the air within the filler 130

tank or tanks is then lowered and the air allowed to escape through the port 49 until the piston-valve has reached the end of its movement toward the right and has traveled through a portion of its movement toward the left. When the port 51 in the piston-valve is again brought in registration with the inlet port 47 in the valve casing, an additional charge of compressed air is admitted and acts upon the foraminous bottoms of the screen pans until the port 51 is closed by passing beyond the port 47. When this port 51 in the piston-valve reaches the exhaust port 48, the compressed air is allowed to escape in the manner just described with reference to the port 49. This action of the air is continued so long as the piston-valve is operated by the motor. It will therefore be apparent that compressed air is admitted intermittently of the filler tanks and frees the openings or meshes in the bottoms of the pans and also lifts the undesirable matter within said pans to allow the paint to pass through said bottoms into the filler tanks.

The mixing vats are considerably larger than shown in the drawings when compared with the filler tanks; and in the use of my invention, it has been found to be unnecessary to empty and clean the screen pans until all of the paint has been discharged from the mixing vats.

My invention assures a free and unobstructed flow of paint to the filler tanks at all times, and also assures maximum filling capacity for the apparatus over any given period of time.

Having thus described my invention what I claim is:—

1. The combination of a filler tank having a delivery controlling device by means of which paint is delivered therefrom to containers to be filled, a removable screen pan extending into the top of said tank and having a downwardly-tapered wall engaging the peripheral wall of said tank at the upper edge thereof in a substantially air-tight manner, means for delivering paint into said screen pan, and means for introducing air into the filler tank below said screen pan.

2. The combination of a filler tank being open at its upper end and having a peripheral wall conformable at its upper edge to pressure applied from the interior thereof, a removable screen-pan having a foraminous bottom and a downwardly-tapered wall extending into the upper open end of said tank and having its downwardly-tapered wall in contact with and exerting pressure against the peripheral wall of said tank at its upper edge and by reason of said conformable wall being rendered air-tight along its circular region of contact, means for delivering paint into said screen pan, and means for introducing air into said filler tank below said screen pan.

3. A filler tank open at its upper end and

containing a quantity of paint, said tank having means at a low point to deliver paint therefrom, a removable foraminous element in said tank engaging the wall of the latter in an air-tight manner near its upper end and separated from the paint within said tank by an intervening space, means for delivering paint onto said foraminous element, and means for delivering compressed air to said intervening space.

4. A filler tank open at its upper end and containing a quantity of paint, said tank having means at a low point to deliver paint therefrom, a foraminous element in said tank engaging the wall of the latter in an air-tight manner near its upper end and separated from the paint within said tank by an intervening space, means for delivering paint onto said foraminous element, and means for intermittently admitting air to said intervening space to clear the openings in said foraminous element and lift matter resting thereon so as to allow the passage of paint therethrough.

5. The combination of a filler tank containing a quantity of paint and having means to deliver paint therefrom at a low point, a removable foraminous wall engaging the wall of said tank at a high point in an air-tight manner, means to deliver paint onto said foraminous wall to be passed through the interstices thereof and accumulate in said tank beneath said wall, and means to intermittently admit compressed air to said tank between said foraminous wall and the accumulated paint in said tank.

6. The combination with a compressed air tank, of a manually controllable filler tank containing a quantity of paint and having means to deliver paint therefrom, said filler tank having a screen separating the space within said filler tank from the surrounding air and engaging the wall of said filler tank in an air-tight manner, a pipe interposed between said compressed air tank and said filler tank and having connection with said compressed air tank and with said filler tank above the level of the paint therein, means for delivering paint onto said screen, and controlling means between said compressed air tank and said filler tank to which said pipe is connected and whereby air is intermittently allowed to travel from said compressed air tank to said filler tank.

7. In an apparatus of the kind described, a plurality of filler tanks having removable screens at their upper ends engaging the walls of said tank in an air-tight manner and through which paint is to be delivered to said tanks, means for delivering paint onto said removable screens, and means to selectively deliver compressed air to said tanks underneath said screens.

8. In an apparatus of the kind described, a plurality of filler tanks having removable

screens at their upper ends engaging the walls of said tanks in an air-tight manner and through which paint is to be delivered to said tanks, means to deliver paint onto said removable screens, and means to deliver compressed air intermittently and selectively to said tanks beneath the screens thereof.

5 In testimony whereof, I affix my signature.

FRANK N. GEORGE.
